UNITED STATES PATENT OFFICE.

WILLIAM F. HUNT, OF NEW YORK, N. Y.

WASHING-MACHINE.

1,244,213.

Specification of Letters Patent. Patented Oct. 23, 1917.

Application filed May 25, 1916. Serial No. 99,728.

To all whom it may concern:

Be it known that I, WILLIAM F. HUNT, a citizen of the United States, and a resident of New Brighton, borough of Richmond, city of New York, county of Richmond, and State of New York, have invented certain new and useful Improvements in Washing-Machines, of which the following is a specification.

10 One object of the invention is to construct a simple, practical machine suitable for washing articles, such as dishes.

15 A further object of the invention is to construct a machine that will occupy a comparatively small space and which will be easy to operate.

20 As showing a specific embodiment of the invention reference is made to the drawings forming a part of this specification and in which drawings,

Figure 1 is a front elevation of a washing machine embodying my invention.

25 Fig. 2 is a vertical sectional view through the central portion of said machine and looking at the machine from the front.

30 Fig. 3 is a vertical sectional view illustrating the detailed construction of a horizontally extending table and a portion of the arm that supports said table.

35 Fig. 4 is a side elevation of the machine looking at the machine toward the operative side.

Fig. 5 is a plan view partially in section and is a view taken as on the plane indicated by the line 5—5 in Fig. 4 looking in the direction of the arrows.

40 Figs. 6 and 7 are detail views of a bucket differing somewhat from the bucket shown in Figs. 4 and 5.

45 The main frame of the machine is designated by 1. A tub or lower casing member 2 is associated with this frame and is preferably carried thereby. This tub or casing can be made of any suitable material so that it will provide a reservoir for holding liquid, for instance, a fibrous material such as is employed in the manufacture of what are known as "paper buckets". A tub or casing of such fibrous material also prevents

50 the loss of heat, does not absorb much heat and thus retains the water hot while in the machine. In other words a "paper" tub is of a material which has a low specific heat and of a material which does not readily

transmit heat. The tub or casing is furthermore practically an inclosing casing which prevents the dissipation of the heat.

A table carrier 3, in the form of a removable arm, extends inwardly from the frame, past a wall portion of the tub and over the lower portion of the tub, that is, over the liquid contained in the tub. A horizontally extending table 4 is revolvably mounted at 5 on the free end of said arm and this table revolves about the vertically extending axis of a trunnion member 6. This table may be provided with any suitable openings, as 7, which may be covered as by means of a screen 8, that is held in place by a retaining ring 9. There is 70 revolvably supported on the frame a bucket carrier 10 and this carrier revolves about the horizontally extending axis 11 of the shaft 12 which supports the bucket carrier. This shaft 12 is located in a bearing 13 on 75 the frame and is actuated as through the medium of a handle 14 and gears 15 and 16. At the free end of an arm of the bucket carrier there is supported a bucket 17, or a plurality of buckets, which is detachably secured in place on said arm by means of three sets of thumb nuts and screws 18. Another arm of the bucket carrier is provided at the free end with a counter-weight, as 19, but manifestly if desired 85 a bucket could be employed in place of the counter-weight 19. The bucket carrier revolves in the direction indicated by the arrow A of Fig. 4 and the bucket 17 passes under the horizontally revolving table 4. 90 In its transit under said table it dips into the liquid in the lower part of the tub 2, picks up some of said liquid, and elevates said liquid until the bucket assumes a position in which the liquid begins to spill from 95 within the bucket; the arrangement of the bucket carrier relative to the horizontally extending table 4 and the shape of the bucket are such that when the liquid begins to spill it drops or pours upon any articles which are supported on and by said table 4.

An inspection of the drawings makes it apparent that the longitudinally extending axis about which the bucket carrier intersects the vertically extending axis about which the table 4 revolves; in other words, the axis of the bucket carrier extends over

the table. Due to this arrangement a compactness of structure is realized in a machine in which the dishes are successively brought under the buckets by the turning of the table 4 as the buckets move from a position below the table to a position above the table. In order that the articles may be properly retained in place on said table there may be employed a cage or reticulated basket 20. As the bucket always travels in the same path the water delivered therefrom will also tend to travel more or less in the same path or paths. In order that all parts of all of the articles on the table will be subjected to the cleaning or scouring action of the water delivered from the bucket—or buckets should more than one bucket be employed—there is imparted at least a partial rotary movement to the table for each revolution of the bucket carrier, thus successively bringing different portions of the table under the water spilled or poured from the buckets. This rotary movement of the table about its vertical axis is obtained through the medium of a gearing 21 between the table and the carrier. This gearing comprises a series of teeth 22 on the periphery of the table and a series of teeth 23 on a sector 24 that is on the bucket carrier 10. By prolonging the sector 24 and continuing the teeth thereupon so as to make a complete circle or gear it will be manifest that a continuous movement could be imparted to the table instead of a step by step or intermittent movement, as will necessarily result if only a short sector, such as 24, is employed. The tub 2, as previously indicated, serves as a reservoir or supply for the water to be used in the washing operation and the water can be drawn from this tub or reservoir by opening the valve 25.

The apparatus is also provided with a cover or upper casing member which together with the lower casing member or tub completely incloses the washing elements, that is, completely incloses the movable members which handle the water or which are subject to the action of the water. The cover just referred to is designated by 45 26 and manifestly can be readily removed from the machine. In machines of this type it is also desirable to be able to readily remove such parts thereof as are subjected to the water and therefore the cage 20, the 50 table 4 and the arm 3 are all made so that they can be readily removed from their supported position. For example, the cage can be readily lifted off the table 4, the table 4 can be readily lifted from its place on the 55 arm 3 and the arm 3 can be swung upwardly and removed from position by merely imparting thereto a slight movement in the direction of the arrow B shown in Fig. 5 a sufficient distance to cause the lug 27 to 60 disengage the notched portion 28. When the

cage 20, table 4 and arm 3 are removed from place the lower half of the tub or casing can also be readily removed by properly positioning the bucket carrier 10, if such removal is desired.

In Figs. 6 and 7 there is shown a bucket which differs somewhat in detail from the bucket shown in Figs. 2, 4 and 5. To the bucket shown in Fig. 6 a screen S has been attached ahead of the entrance end of the bucket whereby only strained water will enter the bucket as it moves through the water. The screen, however, is preferably spaced from the bucket so that the water being spilled or delivered from the bucket 75 will not wash particles off the screen upon the articles being washed.

In Fig. 7 instead of having three screws for holding the bucket in place on the carrier arm there is employed a pin and socket construction comprising a pin 30 which enters a socket 31. In this construction there is employed besides this pin and socket connection a single thumb nut and screws 32. In other words, this bucket can be readily 80 removed from place by merely loosening the nut on the screw at 32 and slipping the pin or pins 30 respectively from the socket or sockets 31. By providing the rotary table with a screen, as 8, or the bucket with 85 a screen, as 29, or by providing both the table and the bucket with screens, it will be manifest that in effect only strained water will be delivered to the articles supported 90 upon the table.

The improvements herein set forth are not limited to the precise construction and arrangement shown and described for they may be embodied in various forms and modifications without departing from the spirit 105 and scope of the invention.

What I claim is:

1. An apparatus of the class described comprising in combination a main frame, a casing or tub, an arm extending inwardly 110 from said frame over said tub, a table carried by said arm and revoluble about a vertically extending axis, a revoluble carrier supported on said frame, a bucket upon said carrier positioned so that as the carrier revolves the bucket will dip into the liquid contained in the tub or casing and will move from a position below the table upwardly to a position where water will be discharged upon articles carried by said table, and 115 means whereby said table and said carrier will be revolved.

2. An apparatus of the class described comprising in combination a tub or casing for holding a washing liquid, an arm carried by a frame and extending over said tub, a revoluble table mounted on said arm and revoluble about a vertically extending axis, a bucket and carrier therefor constructed so that the bucket can pass into the 120

washing liquid in said tub, thence under the revoluble table, thence upwardly to a position where the water will be discharged from the bucket upon the articles carried by said table.

5 3. An apparatus of the class described comprising in combination a table revoluble around a vertically extending axis, a tub located below said table, a bucket movable from position below the table to a position 10 above the table whereby it can pick up a washing liquid contained in said tub and convey the liquid to a position where it will be discharged upon articles supported by the table, and means whereby as the bucket, 15 makes a complete cycle the table will have at least a partial rotation imparted thereto.

4. An apparatus of the class described comprising in combination a horizontally 20 extending table which revolves about a vertically extending axis, a main frame having a member supporting said table, a tub positioned below said table, a revoluble bucket carrier having an arm carrying at the free 25 end thereof a bucket which can be moved from its lower position below the table, where the bucket can pick up a liquid from the tub, to its upper position above the table where the bucket can discharge water 30 upon articles supported by the table, means for rotating said bucket carrier in the manner specified, and means between the bucket carrier and said rotating table whereby at least a partial rotation of the table will be 35 effected for each revolution of the bucket carrier.

5. An apparatus of the class described comprising in combination a frame, a horizontally extending table supported by said 40 frame and revoluble about a vertically extending axis, a tub providing a reservoir for liquid below the table, a bucket, a carrier for moving said bucket from position where it can pick up liquid from said reservoir and 45 pour the liquid upon the articles supported by said table, which carrier revolves about a horizontally extending axis that intersects the vertically extending axis about which the table revolves, and means between the 50 bucket carrier and said table whereby for each cycle of the bucket carrier there will be at least a partial rotary movement imparted to the table.

6. An apparatus of the class described 55 comprising in combination a frame, a table supported by the frame, a tub, a bucket and carrier therefor which is revoluble about a horizontally extending axis, and arranged so that the bucket can pick up liquid from 60 the tub and convey it to a position where it will be poured or projected upon articles supported by the table, and gear means between the bucket carrier and the table whereby for each revolution of the carrier there 65 will be at least a partial revolution of the

table, said gear means comprising a gear upon the periphery of the table which meshes with a sector on the bucket carrier.

7. An apparatus of the class described comprising in combination a tub, a horizontally extending table located over the tub bottom and revoluble about a vertically extending axis, a bucket and a carrier revoluble about a longitudinally extending axis, which carrier moves the bucket from a position between the under side of the table and the tub bottom, where the bucket can pick up liquid from the tub and deliver it upon articles supported by the table, and means between the bucket carrier and the table whereby during some portion of the movement of the bucket carrier at least a partial angular movement will be imparted to the table about its vertical axis.

8. A dish washing apparatus of the class 85 described comprising in combination a frame, a tub or casing carried by said frame, a table supported by said frame over said tub, a bucket and carrier therefor positioned so that the bucket can move below the table 90 and pick up liquid from the tub and convey the liquid to a position where it will be poured from the bucket upon articles supported on the table, means between the table and bucket carrier whereby as the latter rotates there will be imparted to the table at least a partial rotary movement about a vertical axis, and an upper casing member which cooperates with the lower casing member to completely inclose the washing elements comprised in the machine.

9. An apparatus of the class described comprising in combination a frame, a tub, a table above said tub, an arm removably mounted on said frame and supporting said 105 table in such a manner that the table can be revolved about a vertically extending axis, a conveyer having a bucket or buckets thereupon and movable in a path whereby said bucket or buckets can pass below said arm 110 and pick up water from said tub and convey said water to a position where it will be delivered or projected upon articles supported by said table, and means for imparting rotary movement to said table during the 115 movement of the conveyer buckets, the construction being such that the table and the arm can both be removed from the rest of the machine.

10. An apparatus of the class described 120 comprising in combination a frame, a tub or casing for holding liquid, which tub or casing is associated with said frame, an arm carried by the frame and extending inwardly from the frame past a wall portion 125 of the tub, a table over said tub and supported on said arm, means for conveying liquid from said tub to a position where it will be spilled or projected upon articles on said table, and means associated with the 130

last mentioned means for imparting a rotary movement to said table, the construction being such that the arm can be removed by first imparting to the free end of the arm 5 an upward movement and by finally imparting to the arm a lateral movement.

11. An apparatus of the class described comprising in combination a frame, a tub associated with the frame, an arm carried 10 by the frame, which arm extends inwardly past a wall portion of the tub over the bottom of the tub, a table supported on said

arm, means for conveying liquid from said tub to a position where it will be spilled or projected upon articles on said table and 15 means associated with said last mentioned means for imparting a rotary movement to the table.

This specification signed and witnessed this 23d day of May, A. D. 1916.

WILLIAM F. HUNT.
